UNITED STATES PATENT OFFICE.

ANGELO BARBIERI, OF MILAN, ITALY.

ELECTRIC MUSICAL RECORDER.

Application filed June 26, 1923, Serial No. 647,950, and in Italy June 28, 1922.

The present invention has for its subject matter an electric musical recorder consisting in a complex of electric contrivances adapted to automatically write down on paper the music that is being played on keyboard instruments of any type or form.

The apparatus comprises a complex of electric contacts similar to those well known for the transmission of the keyboard movement from one musical instrument to another or to several others, the said complex being here completed by mechanical and electric arrangements adapted for recording on paper the notes as well as the measures.

15 The annexed drawing represents by way of example one execution form of the invention.

Fig. 1 is a vertical section diagrammatically showing the electric arrangement for automatically writing on paper the music played on a keyboard instrument.

20 Fig. 2 is a further vertical section, but on a plan different from the previous one, showing diagrammatically the arrangement 25 for reproducing on the paper the measure of the music that is being written, this being accomplished by striking a suitable blow on a special disc.

Figures 3 and 4 are front sections and 30 show two details in Fig. 2, viz, the detail of the closure of the circuit of the solenoid by which a small hammer recording the measure is operated and a further detail relating to the measure recording mechanism.

35 Fig. 5 is a front elevation of the paper on which the music is being written and shows the paper drums as well as the drive of the measure recording mechanism, the latter being connected to the paper driving 40 drum.

Like figures indicate like parts in the different drawings.

—1— and —2— in Fig. 1 are two keys for instance a white and a black one in the 45 keyboard. By depressing one of said keys, for instance the key —2—, a corresponding plunger —3— is lowered so as to permit the contact lever —4— to touch the fixed contact —5— and therewith close the electric circuit formed by: electric source —6—, conductor 50 wire —7—, terminal —8—, spring —4—, contact —5—, terminal —9—, conductor wire —10—, solenoid —11— and conductor wire —12—. The solenoid —11—, being thus 55 excited, lifts its own core —13— and therewith actuates the lever —14— fulcrumed

at —15—; the lever —14— in its turn swings the lever —16— fulcrumed at —17— and carrying the roller —18— at its free end, whereby the roller —18— strikes on the inkband —19— running upon the rollers —20— —21— —22— —23—. Opposite the roller —18—, on the other side, of the inkband —19—, there is the drum —26— forming part of the three-drum system —25— 60 —26— —27— and pressing down the travelling paper —24— against the band —19— and the roller —18—. The paper —24— travels with a synchronous motion to that of the band —19—; it unwinds itself from the drum —25—, passes under drum —26— and then over drum —27— by which it is entrained at a constant uniform speed. The drum —27— may be driven, for instance, by an electric motor —62— through the gear —60— —61— (Fig. 5) and the necessary adherence between the paper —24— and the drum —27— may be obtained by means of a roller —28— pressed down on the paper by a lever —29—. After leaving the drum —27— the paper passes on the table —30— and thence further on to the place where it is received and made up in rolls or otherwise. Owing to the described arrangement and to the travelling motions of the inkband —19— and paper —24—, any time that the roller —18— is pressed against the underside of the band it will strike a dash on the music line of the paper, at the point corresponding to the key that has been depressed, the length of the dash being smaller or longer according to the length of the note.

It will be readily understood that for each key of the keyboard there will have to be a set comprising a plunger —3—, lever —4—, fixed contact —5—, solenoid —11—, lever —14— and lever —16— with roller —18—.

In order to facilitate reading it may be arranged for instance that all white keys in the keyboard shall mark a straight line and all black keys a sinusoidal line, whereas the line intended for the additional syncopes and for the central note on the paper may be coloured or traced in any other desired manner.

As far as regards recording the time measures, on an extension of the shaft of the drum —27— a disc —31—, is keyed, the disc revolving with the same speed as drum —27— and entraining in its revolution the friction wheel —32—. The latter

can be shifted radially with respect to —31— by the operator depressing the foot lever —33—, the friction wheel —32— being then slid along its spindle —44— by the foot lever —33— across: link —34—, bell-crank lever —35—, link —36—, lever —37— pivoted at —38—, toothed segment —39— reciprocating rack —40—, catcher —41— fixed on —40—, slide —42— mounted on 10 guide rod —43— and whose bottom end is engaged with by the catcher —41— while its top end engages a sliding collar to which the friction wheel —32— is secured. The shaft —44— on which the friction wheel 15 —32— is slideable revolves along with the latter, the two being connected by the shaft feather. To the lower end of the lever —37— a ribbon —45— is attached, the ribbon being arranged beneath the inkband 20 —19— and parallel thereto and bearing the numbers of the Maelzel metronome; the ribbon —45— therefore receives a movement any time the foot lever —33— is operated. When the friction wheel —32— is 25 slid on its shaft —44— from the centre towards the periphery of the disc —31— or reversely, the revolving speed imparted by —31— to —32— and therewith to the shaft —44— and to the roller —45— keyed on 30 —44— will be varied. The roller —45— is made of insulating material and has a metal plate —45"— axially embodied in its periphery. On this metal plate —45"— lie, 35 during the revolution of the shaft —44—, the metal brushes —46—47— to which are connected up the conductors —48—49— leading from the solenoid —50— and forming, in conjunction with the plate —45"— and brushes —46—47—, a circuit fed from 40 the electric source —6—. During the travel of the paper —24— entrained by the drum —27— the said circuit will obviously be closed with greater frequency or with smaller frequency according as by the action of 45 the foot lever —33— the friction wheel —32— has been shifted towards the periphery or towards the center of the friction disc —31—. When the said circuit is closed, the current energizes the coil —50— and the 50 latter's core —51— is lifted. The core —51— in its turn will raise the lever —52— fulcrumed at —53—; the lever —53— will swing the lever —54— fulcrumed at —55— to which it is connected, and the hammer 55 —56— at the outer end of the lever —54— will strike the band —45— and press it against the inkband —19—. The result will be that the inkband will be pressed against the paper —24— and imprint the underlying metronome number thereon; the imprinted number will correspond to the movement imparted to the metronome according to the speed variation imparted to the friction wheel —32—. The recorded measure will 60 be signalled to the player, in order that he 65

may conform to it, by the single-toothed cam —57— keyed on the shaft —44—; at each revolution of the shaft —44— the cam —57— will release the spring —58— working on the disc —59—.

Meanwhile the player will be able to adjust at will, by means of the foot lever —33—, the measure of the quarter which is signalled to his ears and to his eyes by the spring —58— and which is simultaneously 75 marked on the paper by the hammer —56— in the position where the signalling of the quarter begins and with the number corresponding to the movement of the metronome.

As the apparatus makes no records except 80 during the time the key is depressed, the regular and constant travelling motion of the paper will have it as a consequence that the amount of the motion of the wheels is given by the intervals crossed by the dash traced 85 by the key, and the amount of the pauses is given by the blank spaces left between the consecutive notes.

Having now particularly described and 90 illustrated in what manner my invention is to be performed what I claim is:

1. In an electric musical recorder, a plurality of rollers for supporting and guiding a record sheet, one of said rollers consisting of a drive for a record sheet and another of 95 said rollers constituting a platen, an ink band movable coincidently with the drive roller, a pair of levers pivotally connected at their adjacent ends, note recording rollers rotatably mounted in the other end of one of the 100 levers, electromagnetic means associated with the other end of the other lever for actuating the latter, an electric circuit including the electromagnetic means and a circuit closure interposed in said circuit and operable by the 105 key of a musical instrument.

2. A recorder as claimed in claim 1 characterized by the provision of a second magnetic electric device interposed in said circuit, means operable by the second mentioned 110 electromagnetic means for marking time signs on the record sheet, a rotatable circuit closure controlling the second mentioned electromagnetic means, and means for transmitting the rotary movement of the drive 115 roller to the rotary circuit closure.

3. A recorder as claimed in claim 1 characterized by the provision of a second magnetic electric device interposed in said circuit, means operable by the second mentioned 120 electromagnetic means for marking time signs on the record sheet, a rotatable circuit closure controlling the second mentioned electromagnetic means, and means for transmitting the rotary movement of the drive 125 roller to the rotary circuit closure, and pedal controlling means for varying the speed of the rotary circuit closure with relation to the speed of the drive roller for the record sheet.

4. A recorder as claimed in claim 1 characterized by the provision of a second magnetic electric device interposed in said circuit, means operable by the second mentioned electromagnetic means for making time signs on the record sheet, a rotatable circuit closure controlling the second mentioned electromagnetic means, and means for transmitting the rotary movement of the drive roller to the rotary circuit closure and variable and audible time indicating means operated by the rotary circuit closure.
5. A recorder as claimed in claim 1 characterized by the provision of a second magnetic electric device interposed in said circuit,

circuit, means operable by the second mentioned electromagnetic means for marking time signs on the record sheet, a rotatable circuit closure controlling the second mentioned electromagnetic means, and means for transmitting the rotary movement of the drive roller to the rotary circuit closure, manually operable means for varying the speed of the rotary circuit closure with respect to the drive roller, and audible and variable time indicating means operably connected with the rotary circuit closure.

Signed at Milan, Italy, this 9th day of June, A. D. 1923.

ANGELO BARBIERI.
